Specification for Design.

Patented Apr. 29, 1919.

Application filed November 19, 1918. Serial No. 263,223. Term of patent 7 years.

To all whom it may concern:

Be it known that we, NORMAN L. STRAUSS and MAURICE HENRIOT, citizens of the United States, residing, respectively, at New York city, in the county and State of New York, and Arlington, in the county of Hudson and State of New Jersey, have invented a new, original, and ornamental Design for Rings, Buttons, Brooches, Bar-Pins, Hat-Pins, Scarf-Pins, Plaques or articles of similar nature, of which the following is a specification, reference being had to the accompanying drawing, forming part thereof.

The drawing is a plan view of the ring top, showing our new design.

We claim:

The ornamental design for a ring, button, brooch, bar-pin, hat-pin, scarf-pin, plaque, or article of similar nature as shown.

NORMAN L. STRAUSS.
MAURICE HENRIOT.
